EDWARD W. STEVENS, OF DETROIT, MICHIGAN, ASSIGNOR TO CHICAGO PNEUMATIC TOOL COMPANY, OF NEW YORK, N. Y., A CORPORATION OF NEW JERSEY.

TOOL RETAINER.

Application filed July 18, 1923. Serial No. 652,369.

This invention relates to percussive machines, such for example as pneumatic hammers, and more particularly to retaining devices for the working tools of such machines.

5 Among the objects of the invention are to provide a retainer which can be quickly applied and removed in order to facilitate the interchange of working tools, to prevent a working tool from being discharged from a percussive machine if the latter is inadvertently operated when the tool is not pressed to the work, and in general to simplify and to improve prior devices of this kind.

In order to illustrate the invention, concrete embodiments thereof are shown in the accompanying drawings, in which:

Fig. 1 is a side elevational view of a pneumatic hammer having the improved tool retainer mounted thereon;

20 Fig. 2 is an enlarged sectional view of the end of the hammer shown in Fig. 1, taken substantially on the line 2—2 of Fig. 3;

Fig. 3 is a transverse sectional view taken on the line 3—3 of Fig. 2;

25 Fig. 4 is a view similar to Fig. 2 showing the means for mounting a different type of working tool; and

Fig. 5 is a transverse sectional view on the line 5—5 of Fig. 4.

30 A typical use of the invention is illustrated in Fig. 1, wherein the retainer is mounted upon the end of the cylinder A of a pneumatic hammer for the purpose of retaining in operative position so as to be struck by the reciprocating piston B of the hammer, the working tool such as a rivet or button set C, which as indicated in Fig. 2 is provided with a shank c extending within the open end of the cylinder A and with an

40 annular stop flange c'.

The retainer comprises a sleeve 6 of substantial length, the inner or rearward portion of which is adapted to extend over the outer end of the cylinder A and is provided upon its interior with a stop shoulder 7 which engages the cylinder. The outer end of the retainer extends beyond the cylinder A and is provided at its extremity with an inwardly disposed annular flange 8 which

50 cooperates with the flange c' of the working tool C to prevent the latter from being discharged from the percussive machine but permitting limited axial movement of the working tool. A cushioning member such as a

55 spring D may be interposed between the

flanges 8 and c' of the retainer and of the working tool.

The inner or rearward end of the retaining sleeve 6 is provided upon its exterior with spaced parallel annular rings or flanges 60 9 forming therebetween a groove 10. This groove is intersected by one or more slots 11 extending entirely through the sleeve and which in the form shown are two in number and diametrically opposed. Within the 65 groove 10 is seated an open spring ring 12 having locking blocks 13 extending through the slots 11 in the sleeve to engage the cylinder A to securely hold the retainer thereon. While the locking blocks 13 may be 70 made integral with the ring 12 if desired, in the form shown they are separate elements securely fastened to the stiff arcuate spring ring 12 in any suitable manner as by one or more rivets 14. In order to permit the re- 75 tainer to be quickly and easily slipped over the end of the hammer cylinder A, the locking blocks 13 are rearwardly beveled, as shown in Figs. 2 and 4. The cylinder is provided upon its exterior with transverse 80 cuts or slots 15 (Fig. 3) forming shoulders 16 (Fig. 2) behind which the blocks 13 snap when shoulder 7 of the sleeve engages the cylinder.

In using the device with the working tool 85 illustrated in Figs. 1 to 3, the spring D is first slipped over the outer end of the rivet set C and the latter is then inserted endwise into the retainer 6 with the shank c extending rearwardly. The assembled tool and 90 retainer are then forced over the end of the hammer cylinder A until the shoulder 7 of the retainer engages the latter and the blocks 14 snap behind the shoulders 16. The hammer is then ready for use. When it is de- 95 sired to remove the retainer as for the purpose of changing working tools, the retainer sleeve 6 is gripped and rotated either to the left or right sufficiently to cam the locking blocks 13 out of the transverse cuts 15 in the 100 cylinder whereupon the sleeve 6 may be pulled off the cylinder A without difficulty.

Figs. 4 and 5 illustrate the manner of mounting upon the same or a similar hammer, a different form of working tool E such 105 as a chisel, illustrated in full lines in Fig. 4 or a punch indicated in broken line in the same figure. The sleeve retainer 6 remains unchanged but the manner of mounting the tool is slightly different. The shank e of the work- 110

ing tool E has secured thereon in any suitable manner a bushing 20 adapted to fit and close the bore of the cylinder A and which is expanded at its outer end into a flange 21 which abuts the end of the cylinder. In the form shown one or more transversely disposed members such as pins 22 partly intersect the bore of the bushing and cooperate with flats 23 on the shank e whereby the 10 working tool is held against rotary movement but permitted limited axial movement relative to the bushing. As shown and by preference the bore of the bushing 20 is tapered inwardly, and the shank e of the 15 working tool is similarly tapered so that when the tool is pressed to the work, thus disposing the parts in the position shown in Fig. 4, the working tool makes a tight fit with its guide bushing thereby promoting 20 steadiness and accuracy of stroke when the tool is in operation. Relative axial movement of the bushing 20 within the projecting end of the retaining sleeve 6 may be permitted, and such movement of the bushing 25 cushioned by suitable resilient members such as the rubber buffers 24 utilized to partially fill the space between the retaining flange 8 of the sleeve 6 and flange 21 of the bushing. The operation of interchanging 30 tools is the same as that described in relation to Figs. 1 to 3.

From the above it will be apparent that the improved retainer herein disclosed in addition to facilitating the interchange of 35 working tools acts as a safety device since it positively prevents a working tool from being inadvertently discharged, that pneumatic hammers now in use may be readily adapted to take this type of retainer by the 40 simple expedient of cutting two transverse grooves near the open end of the cylinder, and that the retainer is of few parts of rug-

ged construction which can be manufactured and assembled at small cost.

While I have herein shown and described 45 what I consider to be the preferred form of my invention, the same is readily susceptible of modifications and changes to adapt it for use with various types of percussive machines and of working tools therefor within 50 the scope of the appended claims.

I claim:

1. The combination with the cylinder of a pneumatic hammer of a bushing fitting within the open end of said cylinder, a working tool having its shank provided with a flat within said bushing, a pin in said bushing transversely intersecting the bore thereof and engaging said flat on said tool shank to limit the axial movement of the tool relative to said bushing, and a sleeve provided with locking means engaging the cylinder for retaining said bushing in place, said sleeve also serving to keep said pin in said bushing.

2. The combination with the cylinder of a percussive tool of a bushing fitting within the open end of said cylinder and having a flange engaging the cylinder to form a stop, a working tool having its shank within said 70 bushing and provided with a flat, said bushing flange having a transverse bore, a pin loosely fitting within the bore in said bushing co-operating with the flat in said tool shank to limit the axial movement of the 75 tool relative to said bushing, and a retaining sleeve engageable with said hammer cylinder for maintaining said bushing in place, said sleeve also serving to keep said pin in said bushing bore.

Signed by me at Detroit, Michigan, this 80 12th day of July, 1923.

EDWARD W. STEVENS.
